UNITED STATES PATENT OFFICE

127,712

DESIGN FOR AN ELECTRICAL CONTROL PANELBOARD UNIT

William H. Frank, Detroit, Mich.

Application December 7, 1940, Serial No. 97,156

Term of patent 7 years

To all whom it may concern:

Be it known that I, William H. Frank, a citizen of the United States, residing at Detroit, in the county of Wayne and State of Michigan, have invented a new, original, and ornamental Design for an Electrical Control Panelboard Unit, of which the following is a specification, reference being had to the accompanying drawings, forming a part thereof, in which,

Fig. 1 is a front elevational view of an electrical control panelboard unit showing my new design, with a door thereof swung open.

Fig. 2 is a similar view but showing the door closed.

Fig. 3 is an end view of Fig. 1.

Fig. 4 is an end view of Fig. 2.

Fig. 5 is a fragmentary perspective front view.

I claim:

The ornamental design for an electrical control panelboard unit, substantially as shown.

WILLIAM H. FRANK.
